THERMOCOMPRESSOR

John F. Plummer, Jr., Phillipsburg, N. J., assignor
to Ingersoll-Rand Company, New York, N. Y., a
corporation of New Jersey

Application February 19, 1948, Serial No. 9,400

2 Claims. (Cl. 230—104)

1

This invention relates to thermo-compressors of the steam ejector type which are capable of producing high vacuum pressures.

Ejectors of the type to which this invention appertains are normally used in the first stages of a thermo-compressor comprising a plurality of steam ejectors which are connected in series, i. e. with one ejector discharging into the succeeding ejector, in order to produce a high vacuum. With this arrangement, the first and perhaps the second stage ejector will be operating below the pressure at which water freezes, that is, at or below 4.5 mm. mercury and, therefore, the nozzles of these ejectors are constantly subjected to icing conditions. It is apparent then that any moisture present in the propelling steam may condense and freeze in or on the nozzle and thereby impair its efficient operation.

Experience has taught that this undesirable icing characteristic may be eliminated by superheating the steam before it expands through the nozzle. Under normal circumstances, however, a sufficient amount of superheat is not available in the steam header to provide a desired amount of superheat at the nozzle due to the radiant heat loss of the steam in passing from the header to the nozzle. That is, in the first few stages of the thermo-compressor, only a very small weight of propelling steam is necessary to move a large volume of the fluid to be evacuated because of the low pressures to which such fluid is exposed. As a result of this low rate of steam flow, say for example five pounds per hour for the first stage, the per unit, i. e. B. t. u./lb., radiation loss of the steam in passing between the header and the nozzle may become excessive and the steam, though superheated in the header, becomes wet before or upon reaching the nozzle.

The practice has, therefore, been to superheat the steam by an auxiliary or external source of heat at some point near the nozzle thereby preventing icing of the nozzle. Another practice has been to allow the wet steam to expand through the nozzle and in some manner, as for example by an electric heater, heat the nozzle to prevent the formation of ice on its surfaces. These two methods, however, require an auxiliary source of power or heat.

The present invention is to reduce the per-unit heat loss of the steam passing from the header to the nozzle, to such a value that sufficient superheat is retained by the steam to prevent icing of the nozzle. Since the radiation loss of this steam is relatively constant for a given steam temperature, the per-unit heat loss is inversely propor-

2

tional to the flow rate of the steam and, therefore, the per-unit heat loss of such steam may be reduced to the aforesaid value by controlling its flow rate.

It is accordingly one object of my invention to prevent icing of the nozzle of a steam ejector by reducing the per-unit heat loss of the steam being delivered to the nozzle of a steam ejector.

Another object of my invention is to supply steam to the nozzle of a first stage ejector of an ejector series, in excess of that required to operate said ejector and use such excess to operate the succeeding ejector.

Other objects will be in part obvious and in part pointed out hereinafter.

The drawing accompanying this application, in which similar reference numerals refer to similar parts, shows a side view in elevation, partly in section, of a pair of series connected steam ejectors embodying the present invention.

Referring to the drawing, 10 and 11 indicate, respectively, the first two stages of a thermo-compressor the first stage ejector 10 of which is adapted to operate at or below the freezing pressure of water. In furtherance of this end, the ejector 10 is provided with a non-icing nozzle unit 12 mounted on the ejector casing 13 adjacent the inlet 14 for the fluid to be evacuated. Connected between a steam source (not shown) and the outer end of the nozzle unit 12 is a conduit 15 which is designed to convey energizing fluid or steam to the nozzle unit 12 in excess of that discharged into the casing 13 by the unit 12. Such excess is conveyed from the nozzle unit 12 to the second stage ejector to act as the propelling fluid therefor.

In the form of the invention shown, the nozzle unit 12 comprises a nozzle housing 16 having an orifice 17 at the inner end thereof for introducing propelling steam into the mixing chamber 18 of the ejector, wherein the propelling fluid and the fluid to be evacuated are mixed and carried into the diffusor 19. Adapted to bear on the opposite end of the housing 16 is an abutting member 20 which forms an extension for the housing 16 and has an opening 21 therein, whereby a portion of the steam supplied to the nozzle housing is allowed to escape to a point external of the ejector 10.

The abutting member 20 is aligned and held in form relation with the nozzle housing 16 by an internally threaded washer 22 which bears on a sealing ring 23 on the outer end of the housing 16 and is clamped thereto by any suitable means, such as the bolts 24.

In order to minimize the per-unit heat loss of the steam delivered to the orifice 17, means are provided within the nozzle unit 12 and spaced therefrom for conveying steam to a point adjacent the orifice 17, thereby reducing to a minimum the distance traveled by the propelling steam moving at a low rate of flow. In this instance, such means is a tube 25 that forms an extension for the conduit 15 and passes through the abutting member 28 and into the housing 16 to a point adjacent the orifice 17. The lower end of the tube 25 is closed and in the side wall of the tube adjacent the end are perforations 26 to permit steam to escape into the space between the tube 25 and the inner surface of the nozzle housing wherefrom a portion of the steam is discharged into the ejector casing 13 and the excess thereof escapes through the opening 21 into a conduit 27 connected to the nozzle 28 of the succeeding ejector 11.

In the arrangement shown, a three-way valve mechanism 29 is connected in the conduits 15 and 27 to provide selective operation of the ejectors 10 and 11. To this end the valve element 30 of the valve mechanism has two passages 31 whereby the conduits 27 and 15 may be communicated through the nozzle unit 12, as shown in the drawing, or by moving the valve element 30 ninety degrees in either direction the ejector 10 can be cut-off from the source of power supply and the ejector 11 will be directly communicated with the power supply through one of the passages 31. Rotation of the element 30 through an arc of forty-five degrees in either direction from either of the above mentioned positions will effectively cut-off the power source of both ejectors.

It is now obvious to those skilled in the art that the present invention permits the efficient operation of steam ejectors designed to develop high vacuums without the additional expense of auxiliary or external heat source to prevent icing of the ejector nozzles. The present invention provides a simple and inexpensive means for pre-

venting the formation of such ice by reducing the per-unit heat loss of the energizing fluid delivered to the ejector nozzle.

While I have shown and described one form of my invention it is to be understood that various changes and modifications may be made therein without departing from the spirit of the invention as set forth in the appended claims.

I claim:

10. 1. In a thermo-compressor, a plurality of steam ejectors connected in series, nozzles for the ejectors, a tube extending into the nozzle of the first stage ejector and terminating in a plane adjacent the downstream end of said nozzle for supplying steam thereto in excess of that required for operation of the first stage ejector, an opening in the first stage nozzle, and a conduit connected between the said opening and the nozzle of the succeeding ejector for conveying said excess steam thereto.
15. 2. In a thermo-compressor, a first stage ejector connected in series with a second stage steam ejector, nozzles for the ejectors, a tube extending into the nozzle for the first stage ejector and having a closed end lying in the transverse plane of said nozzle adjacent the downstream end thereof, holes through the sides of the closed end portion of said tube for communicating said tube with the interior of the nozzle, and a conduit for conveying steam from the interior of the first said nozzle to the nozzle of the second stage ejector.
